UNITED STATES PATENT OFFICE.

JOSEPH D. KILGORE, OF HOMESTEAD, PENNSYLVANIA.

TOY PISTOL.

1,225,821.

Specification of Letters Patent.

Patented May 15, 1917.

Application filed March 10, 1916. Serial No. 83,325.

To all whom it may concern:

Be it known that I, JOSEPH D. KILGORE, a citizen of the United States, residing at Homestead, in the county of Allegheny and 5 State of Pennsylvania, have invented new and useful Improvements in Toy Pistols, of which the following is a specification.

The present invention relates to toy pistols of the well-known Kilgore type designed for handling cap strips, and provided 10 with a strip feeding and repeating action, so that a repeating cap pistol is provided.

This type of pistol is characterized by a magazine chamber intended to hold a roll 15 of ammunition in the form of a cap strip, combined with strip-feeding and hammer-operating mechanism whereby repeated action on the trigger will give a proper feeding and repeated firing of the cap strip as 20 it is withdrawn from the magazine.

For convenience in loading, it is customary to provide a cap-strip chamber or magazine with a closing gate or shutter 25 pivotally mounted on the pistol, so that it may be readily thrown to open position for insertion of the cap strip and then closed, so as to prevent side spitting of the caps as they are fired.

In the constructions heretofore developed, 30 it has been customary to mount the gate so as to swing downwardly to permit loading, and in some instances, at least, it has been found necessary to provide such gate with springs or other means for maintaining it 35 in its closed position.

Furthermore, in some constructions now known to me, it has been necessary to rivet in the gate, or otherwise positively secure it against displacement, and as these constructions must of necessity be cheap, and the 40 cost of manufacturing and assembling the pistol as low as possible, the elimination of all gate-controlling and gate-securing parts is very desirable.

The object of the present construction is 45 to do away with the necessity of springs or other means for maintaining the gate in its open or closed position, and, furthermore, to simplify the gate-securing means so that 50 when the pistol is assembled, and its main parts are secured together, the gate will be

held in operative position, and its displacement prevented, without resorting to riveting or equivalent gate-pintle securing means.

In the drawings,

Figure 1 is a side view of a pistol embodying my invention with the gate closed.

Fig. 2 is a similar view with the gate open.

Fig. 3 is a sectional view on approximately the line 3—3, Fig. 1.

Fig. 4 is a sectional view on approximately the line 4—4, Fig. 1.

Referring to the drawings by numbers, like numbers indicating like parts in the several views, 10 denotes the pistol proper which 65 is made preferably of two castings designed to be assembled, as shown, to form a complete pistol, with the strip-feeding and hammer-operating mechanism 11 (conventionally shown) between them; a single holding 70 screw 12 passing through the two halves of the pistol at an appropriate point being sufficient to hold these halves with the contained action.

One of the halves of the pistol is provided with a firing abutment 12' and a pintle 13 to receive the cap-roll 14, and the other half of the pistol has a loading aperture to permit the insertion of the cap-roll for engagement with the pintle 13. The loading 80 aperture forms a recess in one of the side members of the frame of the pistol, which recess is open upwardly of the side member. The loading aperture is preferably of sufficient area to uncover the strip magazine for 85 the cap roll 14 and the firing abutment 12' so that the cap roll may be placed easily upon the pintle 13 and the end of the strip threaded or properly placed upon the firing abutment.

After the cap-roll is in position, it is necessary to close the open side of the pistol and this closure is effected by means of the gate 15 which is pivotally mounted in a hollow pintle 16 preferably cast integral 95 with the opposite part of the pistol.

The gate 15 has the pivot 17, which is adapted to be inserted in the hollow pintle 16, so that the gate may be freely turned from its closed to its open position and vice 100 versa.

The gate normally rests in the position

shown in Fig. 1, closing the aperture, and its movement is upwardly and forwardly to the open position shown in Fig. 2. In its open position the gate rests upon the ledge 18 adjacent the forward wall of the magazine chamber, the gate in this position clearing the chamber and leaving it open for the ready insertion of the cap-roll. It will be observed that the gate swings 10 through an angle of approximately ninety degrees, and drops to an open position, from which it may be readily thrown back to close the magazine, and that the need of gate-holding springs, or equivalent devices for 15 maintaining it in either its open or closed position are by this construction done away with.

The gate pivot 17 engages the hollow pintle 16 loosely, so as to turn freely therein, 20 and in order to prevent the gate from becoming disengaged and to avoid the necessity for riveting or otherwise securing the gate-pivot in place within the hollow pintle, I provide a projecting fin 19, which projects 25 outwardly from the base of the gate pivot 17, and when the two halves of the pistol are assembled, lies behind and engages the wall of the pistol, so that while the gate is free to turn, it cannot be moved laterally, 30 and its pivot pin displaced from the bearing pintle. The fin 19 is of such area that it is always in engagement with the inner face of the pistol wall, so that in neither its closed or open position can the gate be- 35 come displaced. At its rear edge, the gate is provided with a projecting lug 20 which drops behind the wall of the pistol and maintains the gate in proper closed position.

The advantage of this construction is that 40 the gate may be applied without the necessity of gate retaining means to insure its proper positioning when closed or open. Its angular movement is small and in such direction as enables the user to open and close it 45 quickly, and the provision of the gate-retaining fin permits me to dispense with the customary riveting or other separate retaining means to insure the maintenance of the gate in proper assemblage with the other 50 parts. As the loading aperture is of sufficient area to uncover both the strip magazine and the firing abutment, the cap roll may be readily positioned in the pistol, and as the loading aperture is open upwardly 55 of the frame of the pistol, the side of the pistol in which the opening is located may be of but one part, the barrel and the handle portions of this part being connected by the strip which lies beneath the loading aperture.

This feature is of considerable value in connection with pistols of this type where the cost of construction and assembling must be kept as low as possible, and it will

be observed that the fin 19 is preferably cast 65 integral with the gate, and after being once assembled with the two halves of the pistol, the single retaining screw or bolt 12 is sufficient to keep the entire construction in proper assembled and operative position. 70

It will be obvious that such departures from the present disclosure as amount to mere mechanical skill may be made without departing from the spirit of my invention.

What I claim is:—

1. A pistol, having a loading aperture in its wall, a gate seat in rear of and below said aperture, a gate pivoted forwardly of and below said aperture to swing upwardly and forwardly in opening, and an abutment 80 at the forward end of said gate seat to support said gate in open position.

2. A pistol, having a loading aperture in its wall, an outstanding gate seat in rear of and below said aperture, and a gate pivoted 85 forwardly of and below said aperture to swing upwardly and forwardly in opening; the forward end of said outstanding gate seat forming a supporting abutment for said gate in open position.

3. A pistol, having a loading aperture in its wall, a gate for said aperture having a single pivot mounted in a suitable bearing in one wall of the pistol frame, and a projection adjacent said pivot to engage the 95 other wall of said frame and prevent displacement of said gate.

4. A pistol, having a loading aperture in its wall, a gate for said aperture having a single pivot mounted in a suitable bearing 100 in the pistol frame, and a circumferential fin at the base of said pivot to engage the other wall of said frame and prevent displacement of said gate.

5. A pistol, comprising complementary 105 sections one of which has a magazine and the other of which has a loading aperture, a gate for said aperture having a single pivot, a pivot bearing on the magazine section, a projection on said pivot to engage the inner 110 wall of said apertured pistol section and prevent displacement of said gate, and a bolt to lock said sections together and said gate between said sections.

6. A pistol comprising complementary 115 sections one of which has a strip magazine and a firing abutment, and the other of which has a loading aperture of sufficient size to uncover both the magazine and the abutment, and a gate for said loading aperture 120 pivoted forwardly of and below the same and adapted to swing upwardly and forwardly in opening.

7. A pistol comprising complementary 125 sections one of which has a strip magazine and a firing abutment intermediate the handle and the barrel portions, the other section having a loading aperture open up-

wardly thereof and of sufficient area to uncover both the magazine and the firing abutment, the barrel and the handle portion of the second section being connected by the 5 strip lying beneath said aperture, and an upwardly swinging gate for said aperture.

In testimony whereof I have hereunto set

my hand in presence of two subscribing witnesses.
